(57) **CLAIM**

The ornamental design for an electronic device with animated graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with animated graphical user interface showing the claimed design;

FIG. 2 is a second image thereof;

FIG. 3 is a front view of another embodiment of an electronic device with animated graphical user interface; and, FIG. 4 is a second image thereof.

The peripheral dashed broken lines depict a display screen or portion thereof, and form no part of the claimed design. The claimed design is illustrated within the dashed line circles the half-tone portion between the peripheral dashed broken lines and the dashed line circles forms no part of the claimed design.

The appearance of the graphical user interface transitions between the images shown in FIGS. 1-2 and FIGS. 3-4. The process or period in which one image transitions to another forms no part of the claimed design.
